UNITED STATES PATENT OFFICE

JAY R. FOGAL, OF SAN FRANCISCO, CALIFORNIA

FUSE

Application filed April 10, 1931. Serial No. 529,161.

This invention relates to fuses and is directed more particularly to electrical fuses embodying venting means to permit the gases to escape when the fuse link melts.

The primary object of the present invention is to provide a novel and improved fuse construction embodying ventilating passages of sufficient length to effectively cool the gases before they are discharged to the atmosphere and thus reduce the fire hazard to a minimum.

Another object is to provide a fuse of this character which shall consist of few parts that are simple in construction and inexpensive to manufacture and which may be easily and quickly assembled.

With these and other objects in view, the invention may be stated to consist in the various novel features of construction and arrangement or combination, all of which will be fully described hereinafter and pointed out in the appended claims.

In the drawings accompanying and forming a part of this application,

Fig. 1 is a view partly in section and partly in elevation of a fuse constructed in accordance with my invention;

Fig. 2 is a plan view of a lock washer employed in my fuse construction;

Fig. 3 is a bottom plan view of one of the end cups;

Fig. 4 is a sectional view taken on the line 4-4 of Fig. 3;

Fig. 5 is a plan view of one of the disks employed in my fuse construction;

Fig. 6 is a sectional view taken on the line 6-6 of Fig. 5;

Fig. 7 is a sectional view of the innermost disk; and

Fig. 8 is a fragmentary sectional view of a modified form of construction.

Referring to the form of fuse illustrated in Fig. 1, 1 denotes the body portion which is preferably cylindrical in shape and formed from insulating material. Positioned with-

in each end of the body portion is a cup shaped member 2 having an internal thread 3 and a tortuous groove 4 formed in the end wall thereof.

A knife blade contact 5 having a reduced portion 6 that is formed with a serrated surface projects through an aperture 7 in the cup shaped member and the edges defining this aperture are serrated as clearly shown in Fig. 4 so that a snug fit is insured between these elements. Disposed within the cup shaped member 2 are a pair of disks 9 and 10 which are formed with serrated openings 11 and 12 respectively to interfit with the serrated surface of the knife blade contact. The peripheral edges of these disks are engaged with the internal thread 3 of the member 2 and define a spiral vent passage 13. From the foregoing description, it will be apparent that the cup shaped member 2, disks 9 and 10, and knife blade contact 5 form a unit assembly.

The disk 9 is formed on opposite faces thereof with tortuous grooves 14 and 15 which are similar to groove 4, and in a similar manner one face of disk 10 is formed with a tortuous groove 16. The grooves 4 and 14, and grooves 15 and 16 cooperate to form a vent passage which communicates at the inner end through lateral ports 17 with the spiral passage 13. Communication is established between grooves 15, 16 and 4, 14 by a port 18 in disk 9 adjacent the inner end of the groove 15. The cup shaped member 2 is formed with a port 19 which extends from groove 4 through the end wall thereof. This member is also formed with ports 20 which extend through the end wall thereof and communicate with the spiral passage formed by internal thread 3.

Closely embracing the knife blade contact is a lock washer 22 formed of two halves pivoted together at 23 and to the fuse body. The ends of these halves overlap at 24 and lie in the same plane. A cap 25 is threaded on the

end of the body portion 1 and encloses the lock washer. This cap is provided with a plurality of ports 26 which communicate with the atmosphere and with the space between the lock washer and cup shaped member 2.

10 A fuse link 27 of any suitable type interconnects the knife blade contacts.

In use, when fuse link 27 melts, the gases generated are vented at each end of the fuse by passing through spiral passage 13 and ports 20 and 26 to the atmosphere. Venting is also accomplished by some of the gases in spiral passage 13 passing through ports 17 thence grooves 15, 16 and port 18 to grooves 4, 14 and ports 19 and 26 to the atmosphere.

15 In assembling the fuse each cup shaped member 4 is pressed on the reduced portion 6 of the knife blade contact and the disks 9 and 10 are then pressed on this reduced portion and into engagement with threads 3. This unit construction is then positioned in the housing 1 and the caps 25 are applied thereto. When the fuse link blows the fuse may be easily and quickly renewed by removing caps 25 and substituting a new link and then reassembling the unit structure in the housing 1.

20 In Fig. 8, I have illustrated a modification embodying a sheet metal cup shaped member 30 having a rolled threaded portion defining an interior spiral passage 31 and an exterior spiral passage 32. In this form of my invention I have illustrated three disks 33, 34 and 35 which have intercommunicating tortuous 25 grooves or passages 36 similar to those described in connection with disks 9 and 10. In other respects the fuse construction is similar to that previously described in connection with Fig. 1. In Fig. 8, a portion of the 30 gases pass through exterior spiral passage 32 and through ports 26^a to the atmosphere. Gases also pass through interior spiral passage 31 thence through the tortuous passages 36 in the disks and ports 26^a to the atmosphere. This form of fuse is assembled and 35 reassembled to renew the fuse link in the same manner as described in connection with Fig. 1.

What I claim is:

40 1. A fuse of the character set forth comprising a body portion, a cup shaped member positioned in each end of said body portion and having an internal thread, a disk positioned within each cup shaped member and engaging said thread to define a spiral passage, said disk having a tortuous passage therein, and means connecting said spiral passage and tortuous passage with the atmosphere.

45 2. A fuse of the character set forth comprising a body portion, a cup shaped member positioned in each end of said body portion and having an internal thread, a plurality of disks positioned within each cup shaped member and having their peripheral

edges engaging said thread to define a spiral passage, said disks having grooves in the faces thereof and the adjacent faces of said disks being in engagement to define a tortuous passage, and means connecting said passages with the atmosphere.

50 3. A fuse of the character set forth comprising a body portion, a cup shaped member positioned within each end of said body portion, a plurality of disks positioned within each cup shaped member, said disks having grooves in the faces thereof and the adjacent faces of said disks being in engagement to define a tortuous passage, and said passage communicating at one end with the interior of said body portion and at the other end with the atmosphere.

55 4. A fuse of the character set forth comprising a body portion, a cup shaped member positioned within each end of said body portion, a knife blade contact projecting through each cup shaped member, a fuse link interconnecting said contacts, means positioned within each cup shaped member and defining an elongated vent passage communicating with the interior of said body portion, a lock washer surrounding each knife blade contact, and a cap enclosing said lock washer and engaged with said body portion, said cap having ports communicating with said vent passage and the atmosphere.

60 5. A fuse of the character set forth comprising a body portion, a knife blade contact projecting from each end of said body portion, a fuse link interconnecting said contacts, a plurality of disks positioned within each end of said body portion and interengaged with the respective knife blade contact, said disks cooperating with each other to define ventilating passages communicating with the interior of said body portion, a lock washer surrounding each contact, and a cap enclosing each lock washer and engaged with said body portion, said caps having ports communicating with said ventilating passages.

65 6. A fuse of the character set forth comprising a body portion, a knife blade contact projecting from each end of said body portion, a fuse link interconnecting said contacts, a plurality of disks positioned within each end of said body portion and interengaged with the respective knife blade contact, said disks cooperating with each other to define ventilating passages communicating with the interior of said body portion, additional vent means communicating with the interior of said body portion, a lock washer surrounding each contact, and a cap enclosing each lock washer and engaged with said body portion, said caps having ports communicating with said ventilating passages and with said additional vent means.

70 7. A unit assembly for a fuse comprising a cup shaped member, and a knife blade con-

tact projecting through said cup shaped member, said contact and member having interengaging serrated surfaces.

8. A unit assembly for a fuse comprising a cup shaped member, a knife blade contact projecting through said cup shaped member, a plurality of disks engaged over said contact and positioned within said member, said disks, member and contact having interengaging serrated surfaces.

10 In testimony whereof I affix my signature.
